UNITED STATES PATENT OFFICE.

JOSEPH S. BLAKE, OF WORCESTER, MASSACHUSETTS, ASSIGNOR TO FLEXIBLE DOOR AND SHUTTER COMPANY, OF WORCESTER, MASSACHUSETTS, A CORPORATION OF MAINE.

FLEXIBLE DOOR.

SPECIFICATION forming part of Letters Patent No. 705,553, dated July 29, 1902.

Application filed May 6, 1901. Serial No. 59,051. (No model.)

To all whom it may concern:

Be it known that I, JOSEPH S. BLAKE, a citizen of the United States, residing at Worcester, in the county of Worcester and Commonwealth of Massachusetts, have invented a new and useful Improvement in Flexible Doors, of which the following is a specification, accompanied by drawings forming a part of the same, in which—

10 Figure 1 represents a front elevation of a portion of a flexible door with the inclosing casing shown in sectional view. Fig. 2 shows a portion of the door with a part of the operating mechanism shown in sectional view; 15 and Fig. 3 is a top view of a portion of a flexible door, showing the operating mechanism.

Similar reference-letters refer to similar parts in the different views.

My invention relates to that class of flexible doors which consist of a series of leaves 20 hinged together at their edges and wound in a coil upon a rod or spindle from which the leaves are unwound in the operation of closing the door, and my invention relates particularly to the apparatus by which the winding and the unwinding of the coil around the spindle or shaft is controlled in the operation 25 of closing and opening the door; and it consists in the employment of a yielding connection between the rod or shaft upon which the door is coiled and a wheel or drum operatively connected with the leaves of the door, so as to be rotated as the door is opened or closed.

30 Referring to the drawings, A denotes a portion of a flexible door consisting of a series of parallel leaves *a a a*, suitably connected at their edges in any well-known method of constructing doors of this class. The edge A' of 35 the door is fastened at suitable intervals to collars, one of which is shown at A² attached to a vertical shaft A³ and supported in suitable bearings at one side of the door-opening. The upper ends of each of the leaves *a* are 40 provided with a projecting pin *b*, said pins being arranged equal distances apart and adapted to engage the teeth of a wheel B, which is attached to a stud B', turning in a bearing B² and having attached to its upper 45 end a pinion C, which is operatively con-

nected with a gear D through an intermediate pinion E, turning upon a stud E'. The gear D is capable of turning loosely upon the vertical shaft A³ and carries a drum or case F, containing a flat coiled spring G, one end of which is attached to the drum or case F and the opposite end is fastened to a collar H, which is attached to the vertical shaft A³. When the door is opened, the several leaves *a a a* are wound in a coil I about the vertical shaft A³. When the door is to be closed, it is drawn in the direction of the arrow J, Fig. 1, and unwound from the vertical shaft A³, the movement of the door in the direction of the arrow J causing the toothed wheel B to be 60 rotated by means of the pins *b*, and the rotation of the toothed wheel B is imparted to the gear D through the intermediate pinion E. The gear D in the operation of closing the door and unwinding it from the coil I causes 70 the blade-spring G to be wound up, so that its tension will be exerted to rotate the vertical shaft A³ in the proper direction to wind up the coil when the door is closed or is moved in the reverse direction to the arrow J or in 75 the direction of the arrow K.

In the operation of opening or closing the door it is moved in a straight line past the toothed wheel B, causing the gear-wheel D to be rotated through the intermediate pinion 80 E. The vertical shaft A³, however, is caused to rotate at a varying speed relatively to the speed of the door owing to the varying size of the coil I. In order to compensate for the variation in speed between the movement of 85 the door and the rotation of the vertical shaft A³, I form a yielding connection between the shaft A³ and the gear D by means of the coiled blade-spring G, which is attached at its opposite ends to the drum F and to the 90 collar H so that the spring will be wound up in the operation of closing the door, causing the tension of the spring to be utilized in rotating the vertical shaft A³ for the purpose of winding up the spring into a coil when the door 95 is opened or moved in the direction of the arrow K, Fig. 1.

What I claim as my invention, and desire to secure by Letters Patent, is—

1. In a flexible door, the combination of a 100

shaft or spindle, a series of leaves hinged together and forming the body of the door having one edge of said door-body connected with said shaft, whereby said leaves are wound 5 into a coil by the rotation of said shaft, of a toothed wheel, means carried by said hinged leaves for engaging said toothed wheel and rotating the same as the door is opened or closed, and an intermediate connecting mechanism between said toothed wheel and said shaft comprising a yielding member, whereby the rotation of said shaft in winding said door-body may be varied relatively to the rotation of said toothed wheel, substantially as 15 described.

2. The combination with a shaft and a flexible door attached to said shaft, of a coiled spring having one end connected with said shaft and having its opposite end operatively 20 connected with said door, whereby the operation of unwinding the door from said shaft will cause said spring to be wound with a uniform movement, substantially as described.

3. The combination with a shaft and a flexible door attached to said shaft, of a coiled spring carried by a wheel or drum and having one end attached thereto and having its 25 opposite end attached to said shaft, means

operated by the door in the operation of opening and closing the same for rotating said 30 wheel or drum, substantially as described.

4. The combination of a shaft, a flexible door attached to said shaft, a coiled spring attached at one end to said shaft, a wheel or drum rotating concentrically with said shaft 35 and attached to the opposite end of said coiled spring, and means for rotating said wheel or drum operated by the movement of the door in opening or closing the same, substantially as described. 40

5. The combination of a door-body composed of a series of leaves hinged together, a shaft upon which said door-body is wound, pins projecting from said leaves, a toothed wheel engaged by said pins, a pinion attached 45 to said toothed wheel, a gear-wheel driven by said pinion and concentric with the shaft upon which the door is wound, and a yielding connection between said gear and shaft, substantially as described. 50

Dated this 29th day of April, 1901.

JOSEPH S. BLAKE.
